UNITED STATES PATENT OFFICE.

NATHAN THOMPSON, OF BROOKLYN, NEW YORK.

IMPROVEMENT IN CARTRIDGE-EXTRACTORS FOR ORDNANCE.

Specification forming part of Letters Patent No. **133,271**, dated November 19, 1872; antedated November 18, 1872.

To all whom it may concern:

Be it known that I, NATHAN THOMPSON, of the city of Brooklyn, in Kings county and State of New York, have invented an Improvement in Cartridge-Extractors, applicable to Breech-Loading Ordnance, of which the following is a specification:

This invention is designed to facilitate the extraction of the cartridge-shell from breech-loading ordnance after the breech-block has been removed from its position for firing; and consists in a novel arrangement of a spring-borne lever to be operated by a spring-borne percussion-rod.

Referring to the drawing, Figure 1 represents a horizontal section of the breech portion of a gun with my invention applied; and Fig. 2 is a rear view of the same, the breech-block in each figure being removed.

The same letters indicate like parts in both figures, and in which—

A represents the body of the gun; B, its bore or barrel; C, the spring-borne lever; and D, the percussion-rod, by which the lever C is operated and caused to extract the cartridge by its underlapping of the flanged end of the latter. E is the breech-block holder, constructed in a similar manner to that described in my applications for Letters Patent, which were al-

lowed March 28, and April 12, 1872, respectively, and therefore need no further description here.

The operation of this extractor will be apparent from the drawing, the breech-block being rolled aside to clear the flange of the cartridge case, in which position it is retained by the screw G, and the spring-rod D, being suddenly projected inward, strikes the lever C, which jerks the cartridge-shell entirely out of its position, the springs by which the lever C and rod D are supported immediately causing said parts to resume their normal position in readiness to receive a fresh cartridge, when the breech-block may be again rolled into position for another discharge of the ammunition inserted.

What is here claimed, and desired to be secured by Letters Patent, is—

In combination with breech-loading ordnance, the cartridge-extractor herein described, consisting of the combination of the spring-borne lever C and percussion-rod D, when arranged for operation substantially as set forth.

NATHAN THOMPSON.
